UNITED STATES PATENT OFFICE.

WILLIAM S. HAYNES, OF BOSTON, MASSACHUSETTS, ASSIGNOR TO WM. S. HAYNES CO.,
OF BOSTON, MASSACHUSETTS, A CORPORATION OF MASSACHUSETTS.

MUSICAL WIND INSTRUMENT.

1,119,954.

Specification of Letters Patent.

Patented Dec. 8, 1914.

Application filed September 12, 1913. Serial No. 789,536.

To all whom it may concern:

Be it known that I, WILLIAM S. HAYNES, a citizen of the United States, residing at Boston, in the county of Suffolk and State 5 of Massachusetts, have invented new and useful Improvements in Musical Wind Instruments, of which the following is a specification.

This invention relates to improvements in 10 musical wind instruments such as flutes, saxophones, piccolos and the like.

Heretofore it has been a common custom to manufacture the tubes of instruments of this nature of silver, brass and German 15 silver. The tone holes which extend laterally through said tubes are provided with flanges which surround said tone holes and project outwardly therefrom. These flanges have been made from material separate 20 from the tubes necessitating a number of operations to form and secure the same to the tubes, also requiring the services of expert workmen to correctly position said flanges on said tubes in order to produce a 25 perfect instrument. During this process the tubes which constitute said flanges are first cut the required length then milled at one end to conform to the transverse contour of the tube and after chamfering the outer 30 ends, said flanges are placed one at a time against the side of the tube, temporarily wired to the tube and soldered in place. The next step is to cut a hole through the tube within said flange and finally finish 35 the inner edges of said holes, as it is absolutely necessary that these edges be carefully rounded and of a uniform curve the entire circumference thereof. There must be no sharp edges or shelves to retard the 40 passage of the air through said tube as when such exist the tone is affected. The flange for the next tone hole is then cut and wired to the tube and carefully measured in relation to said first flange after which it is 45 soldered and finished, as stated and so on, each tone hole being formed in the same manner. It is often the case after a flange has been properly positioned on said tube and during the soldering thereof to said 50 tube that said flange is slightly moved unknown to the workman and after the instrument has been completed and tested it has been found to be imperfect. Such a condition very often exists in the manufacture 55 of instruments of this nature and as the ma-

terial from which they are constructed is very light and expensive it is difficult to remedy the defect. Another decided objection to instruments produced by soldering flanges to the tubes resides in the fact that 60 the solder, which is naturally soft, is very often affected by acid from the hands or from the saliva of the musician which disintegrates said solder and causes the instrument to leak around the tone holes, thus rendering the instrument useless. 65

It is the object of the present invention to produce a tube for instruments of the above nature in which the flanges are formed integral therewith and from material which is displaced from said tube to form said tone holes. By such a construction the tube and flanges, being formed integral throughout, are of substantially the same thickness and said flanges and tube are one integral 70 piece, the result being that there is a decided improvement in the tones which are produced on the finished instrument and in the case of blowing as compared with the metal or wooden instruments which have been 75 made up to the present time in which the flanges are soldered on to the tube and have to be necessarily, in order to make a practical piece of work, of greater thickness than the body portion of the tube. For instance 80 the flanges in practice which are soldered to the tube are made of metal five times as thick as the metal forming the body portion of the tube, so that the solder will have an opportunity to firmly unite the flange to the 85 body portion of the flute. The material constituting said flanges may be pressed outwardly from the interior of said tube by 90 tools which are so constructed that they may form all of said tone hole flanges automatically and simultaneously, thus dispensing with the multiplicity of operations hereinbefore mentioned, one set of tools being sufficient to produce an unlimited number of 95 tubes with a vast saving of metal, as the material which has been heretofore removed to form the tone holes is in the present process employed to form said flanges. 100

Furthermore it is the object of the invention to form the tubes of aluminum for the 105 reason that instruments constructed from same produce a better tone than those constructed of brass or silver. Heretofore this has been impracticable for the reason that the use of solder in connection with this ma- 110

terial is impossible as the heat therefrom warps and twists the tube, but with the present method of forming said flanges integral with said tube, the use of said metal is 5 rendered practicable.

The invention consists in the combination and arrangement of parts whereby the above objects and certain other objects hereinafter appearing may be attained, as set 10 forth in the following specification and particularly pointed out in the claims.

Referring to the drawings: Figure 1 is a plan view of a tube for wind instruments illustrating the irregular arrangement of 15 the various tone holes, the cups or finger pieces being removed. Fig. 2 is a plan view of a section of said tube with the cups and their supports shown in connection therewith. Fig. 3 is a transverse section taken 20 on line 3—3 of Fig. 2. Fig. 4 is a longitudinal section taken on line 4—4 of Fig. 2.

Like numerals refer to like parts throughout the several views of the drawings.

In the drawings, 5 is a metal tube, having 25 a plurality of tone holes 6 therein located at predetermined distances apart longitudinally of said tube and at varying circumferential distances apart. Each of said tone holes is surrounded by a flange 7 which extends outwardly from said tube and is formed integral therewith from material which has been displaced from said tube to form said tone holes, while at the juncture 8 of said flange and said tube the material from which 35 said members are constructed is uniformly rounded the entire circumference of said tone hole, thus providing a smooth surface against which the currents of air passing through the tube 5 may contact, the metal 40 of the flanges being of the same thickness as that of the body of the flute.

The flanges 7 are cut squarely off at 9 and are adapted to be engaged by finger pieces or cups 10 pivotally mounted upon the tube 45 5 in the usual manner well known to those skilled in the art, said cups being normally yieldingly removed from engagement with

said flanges by springs 11, but adapted to be moved to engage said flanges and close said tone hole by a slight pressure of the finger 50 thereagainst.

Having thus described my invention what I claim and desire by Letters Patent to secure is:

1. A metal tube for musical wind instruments having a plurality of tone-holes therein located at predetermined distances apart, each of said holes being surrounded by a flange projecting outwardly from said tube and integral with said tube. 55

2. A metal tube for musical wind instruments formed of aluminum and having a plurality of tone-holes located at predetermined distances apart, each of said holes being surrounded by a flange projecting laterally from said tube and integral with said tube. 60

3. A metal tube for musical wind instruments having a plurality of tone-holes therein located at predetermined distances apart, 70 each of said holes being surrounded by a flange formed integral with said tube from material displaced to form said tone holes.

4. A metal tube for musical wind instruments having a tone-hole therein, said hole surrounded by a flange projecting outwardly from said tube, integral with said tube and of substantially the same thickness of metal as that of said tube. 75

5. A metal wind musical instrument having key seats formed thereon and integral therewith. 80

6. A metal wind musical instrument having elevated key-seat rings thereon drawn from the body of the metal of the instrument. 85

In testimony whereof I have hereunto set my hand in presence of two subscribing witnesses.

WILLIAM S. HAYNES.
